ELECTRIC MOTOR

Charles Lind, Los Angeles, Calif.

Application December 3, 1958, Serial No. 53,641

Term of patent 14 years

(Cl. D26—5)

Fig. 1 is a plan view of an electric motor, showing my new design;

Fig. 2 is a side elevational view, the opposite side being substantially a mirror image thereof;

Fig. 3 is an end elevation taken from the right of Fig. 2;

Fig. 4 is an end elevation taken from the left of Fig. 2; and

Fig. 5 is a bottom view.

The broken line fragmentary showing of a connection cord is for illustrative purposes only.

I claim:

The ornamental design for an electric motor, as shown and described.
